UNITED STATES PATENT OFFICE.

JOHN W. SMEDBERG, OF JAMESTOWN, NEW YORK, ASSIGNOR OF ONE-HALF TO GEORGE L. MALTBY, OF JAMESTOWN, NEW YORK.

TRACK-CIRCUIT RELAY FOR RAILWAY-CROSSING SIGNALS.

1,357,428.

Specification of Letters Patent.

Patented Nov. 2, 1920.

Application filed February 7, 1919. Serial No. 275,528.

To all whom it may concern:

Be it known that I, JOHN W. SMEDBERG, a citizen of the United States, residing at the city of Jamestown, in the county of 5 Chautauqua and State of New York, have invented certain new and useful Improvements in Track-Circuit Relays for Railway-Crossing Signals, of which the following, taken in connection with the accompanying drawings, is a specification.

The invention relates to electrically controlled railway crossing signals; and the improvement consists in providing a simple and easily installed electrical circuit relay 15 for the automatic control of a railway crossing signal, whose action is positive, doing away with all spring action, also doing away with liability to wrong action in the parts of the relay and consequent trouble 20 from an inoperative signal; and the invention consists in the novel features and combinations hereinafter set forth and claimed.

In the drawings Figure 1 is a diagram of the complete electrical track circuit relay for 25 the crossing signal, showing the starting relays in each direction from the central signal operating mechanism. Fig. 2 is a diagram of the electrical signal actuating and stopping mechanism and its connection to 30 the insulated and return rails of the track. Fig. 3 is a vertical sectional view of the stopping relay showing the construction and arrangement of the same with the different 35 positions illustrated in dotted outline. Fig. 4 is a vertical sectional view of the current closing or crossing relay showing the construction and arrangement of the same.

Like characters of reference refer to corresponding parts in the several views.

40 The numeral 10 designates the return rail of the railway track, and the numeral 11 the sectioned rail. The numeral 12 designates the trolley or electrical feed wire. The numeral 13 designates the signal line or connecting wire from the starting relays to the 45 crossing signal.

The signaling system consists of two similar pairs of starting relays, one pair for each direction of travel, and a central signaling mechanism. The starting relays at the right of the diagram consists of the solenoids 14 and 15 placed in spaced relation. The solenoid 14 is connected to the insulated

section 17 of the sectioned rail 11, by means of the wire 16 so that when a car, coming 55 from the right on the track 10—11, bridges said track at the section 17, connection will be made through said car from the insulated section 17 to the return rail 10, from which the current would pass through the wire 18 to 60 the battery 19, thereby energizing the solenoid 14 and raising the core 24 and contact arm 25 against the contact post 26, which contact post is connected to the trolley or feed wire 12 by wire 26.

65 When the contact arm 25 is brought into contact with the contact post 26, the electrical current flows through the wire 30 to the signal wire 13, thence through wire 31 to the resistance coil 32, thence through 70 wire 33 to the circuit closing or crossing signal relay solenoid 34, energizing the same. When the solenoid 34 is energized, the core 35 is drawn upward, thereby drawing up the bar or disk 36 against the contact posts 37 75 and 38, thereby closing the circuit in the wire 39 and 40, which connects through the wire connection 42 to the railway crossing signal 71, the current returning on the wire 43 to the post 45. A tap or branch wire 40 80 connects wire 42 to the upper end of resistance 41 through which a part of the electrical current flows through resistance 41 and resistance 32 connected thereto, thence through wire 33 to solenoid 34 thereby energizing 85 said solenoid and holding the connective bar or disk 36 against the posts 37 and 38.

The energizing current for the solenoid 34 passes out through the wire 44 to the post 90 45, thence to the contact and stopping post 46, upon which the arm 47 normally rests, thence through the plate on the arm 47 to the wire 48, and binding post 49 and wire 50 to the returning wire 51 to the return rail 10. 95

As the car passes forward toward the left it moves both its front and rear wheels in succession off the insulated section 17 of the rail 11 onto the insulated section 23 successively bridging on the rail 10; the solenoid 15 is thereby energized, raising the core 27 and non-contact arm 28 against the underside of the contact arm 25, the current passing through the wire 22, the circuit being completed from the solenoid 15 to the 100 track section 23 by the wire 22, and as soon

as the car passes off the section 23, the bridging connection would be broken and the arms 25 and 28 would fall back to normal positions by gravity and all the parts return to their normal position in readiness for re-use.

The signal actuation will continue, as for example ringing a bell 71 until the car reaches the insulated section 52, at which 10 point the car bridges with the rail 10 and completes a circuit through solenoid 54, so that the current flows through the line 51 to the battery 53, which connects with the solenoid 54, thereby energizing the same, 15 drawing up the core 56 and arm 47, disconnecting said arm 47 from the contact post 46, and breaking the circuit to the crossing signal and to the solenoid 34, thereby allowing the core 35 to drop down upon the stop pin 57 and breaking connection between the contact posts 37 and 38, disconnecting the 20 lines 39 and 40 and returning all parts to normal position for re-signaling, the current through the solenoid 54 continuing in 25 circuit through the wire 53 to the insulated rail portion 52.

As the car continues toward the left, it reaches the insulated rail section 58, thereby giving a bridging connection with the return rail 10 and completing the circuit through the wire 59 to the solenoid 60, battery 61 and wire 62 to return rail 10. Energizing the solenoid 60 draws up the core 63 and non-contacting arm 64 so that 30 said arm presses against the contact post 65, in which position it prevents the contact arm 66 making contact with the post 65, as shown in dotted line in Fig. 1, when the car passes onto the insulated section 67, and 35 thereby through the line 68 energizing the solenoid 69 and draws up the core 70 with the contact arm 66 beneath the end of the non-contacting arm 64, thereby permitting the car to pass on up the line without completing a starting circuit and re-actuating 40 the crossing signal. As the car passes on, it leaves the insulated section 67, thereby breaking the circuit and permitting the parts to return to normal position by 45 gravity.

The description thus far has been given of a car passing from right to left. It is apparent that a car passing from left to right would simply reverse the action since 50 both the starting relays are the same, and either starting relay will actuate the crossing signal; also whichever starting relay is first actuated, the other starting relay will be neutralized by the primary actuation of the non-contacting arms 28 or 64 as the case 55 may be.

In Fig. 1 a side elevation is shown of the crossing relay and stopping relay mechanisms, whereas in Fig. 2 the core is turned 60 so as to show the under and rear sides of the

core and arm and the construction and arrangement of the different parts.

In Fig. 3 the preferred construction for the stopping relay solenoid is shown with the preferred arrangement of the core and 70 pivoted contact arm, and Fig. 4 shows in section the crossing relay solenoids and the preferred construction and arrangement of the same, including the laminated core 35. All of these parts are made simple and with 75 a positive actuation, entirely doing away with springs so that said parts are operative under all weather conditions and may be made to operate on either battery or low voltage alternating current. Connections 80 are made directly to trolley or feed wire. This positive action is largely attained by the parts dropping into normal position by gravity, thereby greatly simplifying the 85 construction as well as strengthening the 90 parts.

The solenoid cores are preferably laminated for alternating current, as shown at 35 and 56 in Figs. 3 and 4, while they are left solid for direct current.

I claim as new:

1. An electrical control for a railway crossing signal comprising railway tracks, starting relays a spaced distance from a crossing signal relay mechanism, insulated track sections in one rail of said tracks, said relays connected in circuit with the opposite rail and said insulated track sections, a car adapted to close said circuits by bridging said tracks at said sections, the parts of said 95 starting and crossing relay mechanism arranged to drop into normal position by gravity.

2. A railway crossing signal mechanism comprising a signal actuating relay and a 105 stopping relay at the point of railway crossing, starting relays a spaced distance each side of said signal actuating and stopping relays in combination with a railway track, one of the rails of said track insulated in 110 sections near said relays, the other rail of said track used as a return rail for the electrical circuit through the starting relays, said relays connected in circuit with said insulated track sections and return rail so as to 115 close said circuits by a car bridging said tracks, and all the parts of said relay mechanism adapted to drop into normal position by gravity.

3. An electrical control for a railway 120 crossing signal comprising a signal actuating relay solenoid having a vertically dropping core and a stop for said core, a stopping relay solenoid having a vertically dropping core and contact arm pivotally attached to the lower end of said core to drop 125 by gravity onto a contact post, a two-piece resistance connected in circuit with said signal actuating relay and said stopping relay contact arm, a track composed of a sectional 130

65 rail and a return rail, the latter connected in circuit with one terminal of said stopping relay solenoid, said contact arm and one terminal of said signal actuating relay, said
 5 sectional rail having its sections insulated from each other and one section connected in circuit with the stopping relay solenoid whereby the latter will be energized by a
 10 passing car bridging the track at the specified rail section, a trolley wire, the other terminal of the signal actuating relay solenoid adapted for connection with the trolley wire, and means connected in circuit with another rail section for electrically connecting the
 15 latter terminal of the signal relay solenoid to the trolley when the track is bridged at the second rail section.

4. An electrical control for a railway crossing signal comprising a railway track
 20 composed of a return rail and a rail containing insulated track sections, starting relays comprising two solenoids connected in circuit with adjacent insulated track sections, a contact post in a signal control circuit, one of said solenoids having a contact arm to be drawn into contact with said post when the car bridges its respective insulated section of said track and so close said control circuit, the other solenoid having a non-contact arm to be drawn against the lower side of said contacting arm when said arm is in contacting position against said post to maintain the signal control circuit.

5. An electrical control for railway signals, comprising a track one of the rails of which consists of insulated sections, a signal, means on each side of the signal and connected to adjacent insulated sections of said rail for operating the signal when a car passes
 35 over the respective insulated section, and other means associated with each first means and connected to an adjacent insulated section for mechanically rendering the associated first means inoperative when said first means follows its associated second means in sequence of operation.

6. An electrical control for railway signals, comprising a track one of the rails of which consists of insulated sections, a circuit including the rails, a signal, electro-magnetic means connected to one insulated section and including a member for closing the circuit to operate the signal as a car passes over said section, and electro-magnetic
 50 means connected to another section and including a member for rendering the first named member inoperative when the latter section is reached by the car in advance of first section and for sustaining said first member when the track is traversed in a reverse direction.

7. An electrical control for electric signals, comprising a track the rails of which are included in a circuit and one of the rails of

which consists of insulated sections, a trolley wire, a signal, a car for bridging the circuit across the rails, and means for actuating the signal including a pair of electro-magnets connected to adjacent rail sections and the opposite rail, a swinging contact arm operable by the armature of one magnet, a signal wire with which the arm is electrically connected, a fixed contact connected with the trolley wire and against which the arm is movable to close the circuit and a non-contact arm operable by the other magnet to obstruct the contact arm when operated prior thereto and to hold the contact arm in engagement with the fixed contact when operated subsequent thereto, the sequence of operation of the arms corresponding to the direction of travel of the car.

8. An electrical control for electric signals, comprising a track the rails of which are included in a circuit and one of the rails of which consists of insulated sections, a trolley wire, a signal, a car for bridging the circuit across the rails, and means for actuating the signal including a pair of electro-magnets connected to adjacent rail sections and the opposite rail, a swinging contact arm operable by the armature of one magnet, a signal wire with which the arm is electrically connected, a fixed contact connected with the trolley wire and against which the arm is movable to close the circuit and a non-contact arm operable by the other magnet to obstruct the contact arm when operated prior thereto and to hold the contact arm in engagement with the fixed contact when operated subsequent thereto, the sequence of operation of the arms corresponding to the direction of travel of the car, a resistance connected to the signal wire, a normally open connection between the trolley wire and the signal, an electro-magnet for closing the normally open connection and connected to the resistance, a normally closed switch arm closing the circuit through the third electro-magnet the signal and the solid rail, and an electro-magnet connected to another rail section and to the solid rail for opening the switch arm.

9. An electrical control for railway signals, comprising a track one of the rails of which consists of insulated sections, a circuit including the rails and a signal and comprising a switch including in the circuit, means for operating the signal, and a single means operable both prior and subsequent to the first means, depending upon the direction of travel of a car over the rail sections, for withholding operation of the switch and for holding it operative, respectively.

10. An electrical signal control including a trolley wire, a track one of the rails of which consists of insulated sections, a signal, a normally deenergized electro-magnet

adapted when energized to close connection between the signal and trolley wire, an electrical connection between the other rail of the track and the electro-magnet, an auxiliary circuit including a secondary source of electrical energy and an electro-magnet connected to the continuous rail and one section of the sectional rail, and other electrical connection between the trolley and the first

electro-magnet adapted to be closed by the 10 armature of the second electro-magnet.

In testimony whereof I have affixed my signature in the presence of two witnesses.

JOHN W. SMEDBERG.
